UNITED STATES PATENT OFFICE.

WILLIAM H. FLETCHER, OF PATERSON, NEW JERSEY.

DYEING-MACHINE.

No. 872,807.

Specification of Letters Patent.

Patented Dec. 3, 1907.

Application filed June 14, 1906. Serial No. 321,698.

To all whom it may concern:

Be it known that I, WILLIAM H. FLETCHER, a citizen of the United States, residing at Paterson, in the county of Passaic and State 5 of New Jersey, have invented a new and useful Dyeing-Machine, of which the following is a specification.

My invention relates to improvements in machines for dyeing skeins of silk or other 10 threads: and the objects of my invention are economy in construction and in liquid used; rapidity in loading and unloading the machine, and the prevention of tangles so that the threads will wind well. I attain these 15 objects by the mechanism illustrated in the accompanying drawing, in which—

Figure 1 is a side view of the machine. Fig. 2 is an end view of the same. Fig. 3 is a side view of the frame for holding the skeins. 20 Fig. 4 is an end view of Fig. 3. Fig. 5 is a detail of a part of Fig. 3. Fig. 6 is an end view of Fig. 5. Fig. 7 is a view of the piece for holding the bottom rolls in place with the guide wire on it. Fig. 8 is a view of the piece 25 for holding the upper rolls. Fig. 9 is an end view of Fig. 7. Fig. 10 shows two views of the catch for holding the upper piece, as shown in Fig. 8, in place. Fig. 11 is two views of a similar piece for holding the piece, 30 as shown in Fig. 7, in position. Fig. 12 is an end view Fig. 8. Fig. 13 is a stud which connects the link which operates the frame with the crank. Fig. 14 is a view of the top roll over which the skein hangs. Fig. 15 is a 35 view of the bottom roller. Fig. 16 is a view of the crank for operating the frame. Fig. 17 is a side view of the connecting link. Fig. 18 is a handle for revolving the skeins.

Similar numerals refer to similar part 40 throughout the several views.

A frame, 1, supporting the hoisting and operating mechanism is located around and above an ordinary vat 2 which contains the liquid and the frame with the skeins on it.

45 The frame for holding the skeins consists of the corner pieces 23 the upper connecting piece 59 which supports the one end of the rollers 48 in a bearing so that they remain supported in the same position, without the 50 other end being supported, the corresponding bottom back piece is similar to the piece shown in Fig. 8 except that it is rigid in the frame and as shown it consists of a number of slotted openings to permit of raising the

one end of the bottom roller, pivoting on a 55 rod 25, said rod is secured to the frame piece by studs 54, the slots in the bar keeping the rollers in position.

The front end of the top rolls are supported when the goods are placed on them 60 by the piece 26 shown in Fig. 8 the ends 30 are slipped over the catches 31 which are secured to the corner pieces 23 these catches can be turned around in the frame to fit the piece 26 in place. 65

The bottom roller is pressed down in openings in the piece 24 to receive them and the piece 27 is placed on top of said roller ends and the piece 27 is secured there by the pieces 34 by turning them on their round 70 portion 57 by which they are swiveled in the frame 23. On the bottom roll the shell 50 turns on the bar 49 which pivots on the rod 25.

When the piece 27 is removed and also 75 the piece 26 the bottom roll will be in position as shown at 52 in Fig. 6 and the front end of the upper roll will be clear so that the skeins can be easily taken off, or put on.

The upper rolls have gears 43 on them, 80 which mesh in each adjacent one so that their motion is as indicated by the arrows shown in Fig. 5 these rollers also have wires 40 between the gear 43 and the head 41 usually three so that the goods will not lie on any 85 more of the roller than is necessary to prevent a shading or marking of the goods. The gears are operated by the elevated gear 44 which meshes into the gear 43, in this gear 44, there is a square hole to receive the 90 handle 47 by which it receives the required turning.

On the frame 1 there is a shaft 7 with two cranks 8 in it; on this shaft there is a gear wheel 3 and is driven by the gear wheel 4, 95 this last named gear has a tight and loose pulley 6 by its side, on the same shaft, which is driven by the belt 5.

The two cranks 8 are connected to the frame on which the two studs 11 are, by the 100 links 9, the one end 10 of which drops over the said studs.

When the machine is started the cranks oscillate the frame with the goods in the liquid this moving forward and backward 105 keeps the liquid well mixed and causes it to enter every portion of the skein and thus thoroughly dye the thread. I find that if the

machine is stopped and then the skeins are turned by means of the handle, they do not tangle, and wind well when worked afterward, this is the reason I do not revolve them when the machine is in operation automatically. There are guard rods, 36, 37, 38, and 39 for the purpose of keeping the skeins from the sides of the frame.

There are two shafts 12 at the top of the frame on which there are two drums 13 on each over which a chain 14 is wound and the other ends are connected to the portions 22 of the frame, thus supporting the frame in the clear; 22 of the frame, on the ends of these shafts 12 there are worm gears 17 which are driven by the two worms 15 on the shaft 60 and on this same shaft there is a tight and loose pulley 16 to drive it, and also a sprocket and a chain belt 18 driving it from the sprocket gear 19 on the shaft 20 on which there is also a handle 21, which can assist or operate the drums independently from the tight and loose pulley; by this means the frame with the goods can be and is raised from out the liquid, and lowered again when loaded, after first disconnecting the link 9.

By this apparatus I save time in loading and unloading, and get an even and perfect dye, with very little liquid used in proportion to the work dyed.

Having thus described my invention what I claim and desire to secure by Letters Patent is:

In a dyeing machine, the frame for supporting the reels and rollers on which the goods are, the top reels supported at one end in the frame, and the other end supported by the slotted piece 26 held in place by catches 31, said reels consisting of a center 35 bar or tube, the rods 40 and the heads 41 and having gears on the one end of the said reels, in connection with the bottom rolls, consisting of a tube, or rod with another tube or shell on said rod, the said bottom 45 rolls pivoting on a rod 25, the rod being secured to the frame 1 by the studs 54; the piece 27 for holding the bottom rollers in place, the buttons 34 for securing the said retaining piece 27 in place and the guard 50 rods 36, 37, 38 and 39 for the purpose of keeping the skeins from the ends of the rollers and to prevent the goods from catching or rubbing as described and set forth in the drawings and specifications. 55

Signed at Paterson in the county of Passaic and State of New Jersey this 4th day of June A. D. 1906.

WILLIAM H. FLETCHER.
